(57) **CLAIM**

The ornamental design for a display screen or portion thereof with a graphical user interface for displaying agricultural data, as shown and described.

DESCRIPTION

The file of this patent contains a least one drawing executed in color. Copies of this patent with color drawing(s) will be provided by the Office upon request and payment of the necessary fee.

FIG. 1 is a front view of a first embodiment of a display screen or portion thereof with a graphical user interface for displaying agricultural data in accordance with the claimed design;

FIG. 2 is a front view of a second embodiment thereof; and, FIG. 3 is a front view of a third embodiment thereof. The outermost broken lines in the figures show a display screen or portion thereof, and form no part of the claimed design.
